SWITCH

Newton C. Schellenger, El Paso, Tex., assignor to
 Chicago Telephone Supply Company, Elkhart,
 Ind., a corporation of Indiana

Original application June 6, 1936, Serial No.
 83,963. Divided and this application April 27,
 1939, Serial No. 270,281

7 Claims. (Cl. 201—55)

This invention relates to a new and improved construction of a combined variable resistance and switch and more particularly to such a combination in which the switch is electrically shielded from the variable resistance.

This application is a division of my copending application Serial No. 83,963, filed June 6, 1936, and a continuation as to all common subject matter of my copending application, Serial No. 10 54,407, filed December 14, 1935.

While my improved switch and variable resistance combination may be used for controlling any electrical circuits which do not exceed the power carrying capacity of the switch it is especially adapted for use with radio sets to control the current supplied to the set.

My improved construction is particularly adaptable for use in automobile radio sets which are designed and manufactured to have a very high 20 sensitivity which is required by the comparatively small antennae with which they are operated. Recently because of the use of the so-called "turret top" or one-piece metal top on automobiles, the antennae have been placed under the car 25 or under the running board where they are smaller than those formerly used in car tops, and also are less effective due to closer proximity to ground. For these reasons automobile radios are now made with an even higher degree of sensitivity.

30 The highly sensitive automobile radio must be shielded from the high frequency disturbances set up by the ignition system of the automobile. Since the ignition system and the radio are operated from the same battery, these disturbances 35 must be prevented from reaching the sensitive set circuits through the power supply lines. An even more important factor in automobile radios and also a factor in certain types of home radios which are now designed to operate entirely from

40 a six volt battery is the interference created by the vibrator type of high voltage supply for the radio set. This type of high voltage supply includes a vibrator which breaks up the six volt primary of a step-up transformer into a very 45 rough wave form which is also, of course, present in the high voltage secondary circuit. The switch which controls the current supply to the heaters or filaments of the tubes controls the six volt supply to the vibrator and as a result, any 50 resistance in series with these two circuits will cause a voltage drop due to each component. The voltage drop due to the vibrator component will have the same wave form as the current and will be impressed upon the leads going into the 55 heaters or filaments of the tubes and will thus

convey interference into the set. This effect can be minimized or substantially eliminated by the use of a low resistance switch. This rough wave form will further cause an electrostatic transfer from the switch to the volume control unless 5 adequate shielding between them is provided.

With many types of combination switches and variable resistances now in use, the switch cam is formed of metal and is insulated both from ground and from the current carrying portions 10 of the switch when the switch is in the closed position. While shielding is interposed between the current carrying portions of the switch and the resistance, there is none interposed between the current carrying portion of the switch and the cam and none between the cam and the variable resistance. This means that the metal cam structure can act as a transfer agent from the switch enclosure to the volume control enclosure 15 by the process of re-radiation, minimizing to a 20 certain extent the effectiveness of the switch shield.

It is an object of the present invention to provide a new and improved switch construction.

It is a further object to provide a shield construction in combination with such a switch.

It is another object to provide a switch construction in which the switch operating cam serves as a portion of the shield between the 30 switch and variable resistance.

It is an additional object to provide a switch composed of but few and simple parts and adapted for easy assembly.

It is another object to provide a switch which is comparatively inexpensive to manufacture and adapted for commercial production and use.

Other and further objects will appear as the description proceeds.

I have shown certain preferred embodiments 40 of my invention in the accompanying drawing, in which—

Figure 1 is a view in elevation showing the improved switch applied to a variable resistance;

Figure 2 is a view of the combination of Fig- 45 ure 1 on a somewhat larger scale and taken sub-stantially on line 2—2 of Figure 1, with the hous-ing members in section, the variable resistance shield disc partly in section, and the remaining parts shown in elevation;

Figure 3 is a section of the combination device of Figure 2 taken substantially on line 3—3 of Figure 2;

Figure 4 is a plan view of the switch housing assembly shown in Figure 1; and

Figure 5 is a perspective view of the switch actuating member.

Referring to the drawing, the variable resistance unit is provided with the housing 10, which supports the switch housing 12. The housing 10 is a cup-shaped member having a top portion 14 which serves as a fixed metallic shield between the switch and the variable resistance. The switch housing 12 is provided with a plurality of ears 16 which extend through elongated perforations in the top portion 14 of the housing 12, and are turned over against the under face of the portion 14 to firmly secure the switch housing in place upon the variable resistance housing.

This connection between the switch housing 12 and variable resistance housing 10 also serves to electrically connect the two housings. The intermediate shield portion 14 of the housing 10 is provided with the opening 18 through which the switch cam 20 projects.

The variable resistance device is controlled by the shaft 22 which is journaled in the thimble 24 and carries the disc 26 which is retained on the inner end of the shaft 22 by the swaged inner end 27 of the shaft. The rotating disc 26 carries the switch operating pin 28 which coacts with the switch cam 20.

The base 30 of the variable resistance device is formed of sheet insulating material and the metal shield plate 32 is carried upon its outer face. The flange 34 on the inner end of the thimble 24 engages the inner face of the base 30 and the portion 35 of the thimble retains the washer 36 against the outer face of the plate 32, to retain the base elements in assembled relation. The assembled unit may be supported on a panel or chassis flange indicated in broken lines 38 on Figure 1 by means of a nut 40, screwed upon the threaded portion 25 of the thimble 24.

As will be seen in Figures 1 to 3 inclusive, the major portion of the cylindrical flange of the housing 10 extends beyond the edge of the base member 30 and the housing 10 is provided with ears 42 which are bent over against the plate 32 to secure the housing 10 to the base 30. The insulating strip 44 extends around the inner face of the cylindrical wall of housing 10 and serves to space the shield wall 14 at a predetermined distance from the base 30. The base 30 is provided with an extended portion 31 to carry the terminals and the housing 10 is cut away at 11 as shown in Figures 1 and 3 to clear the extended portion 31 and the terminals. The insulating strip 44 substantially closes the cut away portion 11. The lateral edges of this portion 11 engage the edges of the extended portion 31 of the base and thus have the function of definitely and permanently locating the housing 10 and the switch supported thereby, relative to the base.

The arcuate strip 46 carries the film or layer of resistance material 47. This strip 46 may be formed of paper, fibre, sheet bakelite or similar material and is secured to the base 30 by the terminals 48 and 49 and the rivets 50 and 51. The insulating washer 52 fits about the shaft 22 against the inner end of the thimble 24 and carries a collector ring 54 which has a downturned locating lug 55 extending into the notch 53 of washer 52 as shown in Figure 3. The ring 54 is also provided with the connecting extension 56 which passes downwardly through the opening 57 in the base 30. The center terminal 58 is connected to the extension 56 by means of the rivet 60 which passes through the extended portion 31 of the base 30.

The insulated contactor drive disc 62 is mounted upon shaft 22 below the metallic disc 26 and is provided with a notch 64 into which extends the downturned lug 66 on the disc 26. The interengagement of this lug 66 and notch 64 causes the disc 62 to rotate with the shaft 22 and disc 26. The contact drive arm member 68 is secured to the under side of the disc 62 by means of rivet 69 and engages the collector ring 54. The contactor 70 is provided with the upstanding ears 71 by means of which it is driven by member 68. The member 68 is provided with an upturned lug 72 which engages in the notch 64 of disc 62 to assist the rivet 69 in properly locating the member 68 relative to disc 62 and shaft 22. The shaft 22 has the groove 73 formed therein to receive the C washer 74 which serves to maintain the parts in assembled relation.

The switch base 76 is held in the switch housing 12 by means of the inturned flange 78 on the outer edge of the housing and by the inturned lugs 80 which engage the inner face of the base. The flange 78 is cut away at 79 to provide ample clearance between the flange and the terminal 89. The base 76 is notched to engage the inwardly bent portion 82 of the housing 12 as shown in Figures 1 and 2. The flange 78 is extended at 83 to cover this portion 82 (see Figure 4). The indented portion 82 of the housing serves not only as a stop and grounding contact for the switch cam 20 but also serves to positively locate the base 76 relative to the housing 12.

The pivot member 84 is riveted in place in the base 76 and supports the switch cam 20. The fixed contacts 86 and 87 are riveted to the base 76 by means of reduced extended portions 90 and 91 which also serve to rivet in place the connecting lugs 88 and 89 on the outer face of the base member. The fixed contacts 86 and 87 are cylindrical in form and may be silver plated or otherwise treated to reduce resistance.

The elongated movable contact member 100 is carried between the switch arm 92 and the base 76. This member 100 is of a thickness less than the height of the fixed contacts 86 and 87 and consequently fits somewhat loosely between the switch arm and base since the switch arm is held away from the base by the fixed contacts.

The switch cam 20 is formed as a unitary metal member which is U-shaped, with an upper leg 120, a lower leg 122 and a connecting portion 124. The lower leg 122 has an opening 123 which fits on the pivot 84 adjacent an enlargement thereon. This portion is also provided with the opening 117 receiving the end of the spring 112. The lower leg 122 has formed thereon the lugs 128 and 129 which alternately engage the portion 82 of the switch housing 12 so that the switch cam is grounded to the housing in both the on and off positions of the switch.

The upper leg 10 is provided with an opening 121 which fits on the pivot 84. The openings 121 and 123 are in alignment and give the cam 20 a double bearing on the pivot so that it operates freely and without binding.

The switch is comparatively simple in design and in assembly, and efficient in operation. The housing assembly is important in that it permits the manufacture of a switch of this character without the necessity for the use of any expensive molded housings. The use of the indent 82 in the switch housing 12 permits the formation of a stop without additional material or separate assembly operations, the stop serving both to locate the switch base 76 and to stop and ground

the switch cam 20. The fixed contacts are solid members which are simpler to assemble and adjust than spring contacts which are often used for this purpose and which require careful adjustment as to position and resilient thrust.

5 In the operation of the switch it will be apparent that with the switch in the off position, the portion 129 of the switch cam 20 engages the indented portion 82 of the switch housing, thus not only limiting the movement of the cam but effectively grounding the cam. With the switch in the on position the portion 128 of the cam 20 engages the indented portion 82. The lower leg 122 of the switch cam 20 overlies the opening 18 in the housing 10 of the variable resistance. The switch pivot 84 and the upper leg 120 of the cam extend through this opening in the housing. This mass of grounded metal overlying the opening and extending through it serves as an effective 10 shield to prevent any electrical coupling, whether electrostatic, electromagnetic or capacitive in character, between the fixed switch contacts and the movable switch contact, all of which are located eccentrically of the opening 18 in the 15 housing. This cam is effectively grounded when the switch is in closed position, at which time the electrical apparatus with which the combination device is associated is in use. Therefore the shielding is fully effective when the device is in 20 use and prevents any transfer of hum or other electrical disturbance from the switch to the 25 variable resistance.

While I have shown certain preferred embodiments of my invention, these are to be understood to be illustrative only, as I contemplate such changes and modifications as come within the spirit and scope of the appended claims.

I claim:

1. In combination: a variable control unit for 40 use in highly sensitive radio circuits, having a rotatable operating shaft; a metal casing for said variable unit, said casing having end walls, one of which carries a bearing for the rotatable operating shaft; a substantially cup-shaped metal 45 housing having its open end mechanically and electrically connected with the other end wall of said casing; said other end wall of the casing having an aperture therethrough; switch mechanism in said housing including a metal switch actuating cam having a portion closely adjacent to the wall and overlying said aperture to cooperate with the apertured wall for shielding the switch from the control unit; means providing a transient operating connection between the shaft and the 50 cam for actuation of the switch; and a metal stop on the switch housing engaged by the cam when the switch is closed for grounding the cam to the housing and casing.

2. In a combined switch and control unit for 60 radio circuits of the type wherein a single rotatable shaft operates both the switch and the control unit: a substantially cup-shaped metal casing for the control unit having an aperture through its bottom wall considerably smaller than the total area of said wall; a metal housing for 65 the switch having one open side; means for mechanically and electrically connecting the housing to the bottom wall of the cup-shaped casing so that said wall closes the open side of the 70 housing to electrically shield the switch from the control unit; a metal actuating cam for the switch projecting through said aperture and having a portion overlying the aperture to substantially 75 close the same; and cooperating means on the cam and the metal switch housing providing a

metal to metal contact between the cam and switch housing to limit the motion of the cam in switch closed position and ground the cam to the connected housing and casing so that the cam coacts with the apertured bottom wall of the casing in shielding the switch from the control unit.

3. In a combined switch and control unit for 10 radio circuits of the type wherein a single rotatable shaft operates both the switch and the control unit: a substantially cup-shaped metal casing for the control unit having an aperture through its bottom wall considerably smaller than the total area of said wall; a metal housing for 15 the switch having one open side; means for mechanically and electrically connecting the housing to the bottom wall of the cup-shaped casing so that said wall closes the open side of the housing to electrically shield the switch from the control unit; a metal actuating cam for the 20 switch projecting through said aperture and having a portion overlying the aperture to substantially close the same; an inward integral indentation in the side wall of the switch housing; and an extension on the metal cam engageable 25 with said indentation in the switch closed position to ground the cam to the connected housing and casing so that the cam complements the apertured casing wall and assures more complete shielding between the switch and the control unit. 30

4. In a combined switch and control unit for 35 radio circuits of the type wherein a single rotatable shaft operates both the switch and the control unit: a substantially cup-shaped metal casing for the control unit having an aperture through its bottom wall considerably smaller than the total area of said wall; a metal housing for 40 the switch having one open side; means for mechanically and electrically connecting the housing to the bottom wall of the cup-shaped casing so that said wall closes the open side of the housing to electrically shield the switch from the control unit; a metal actuating cam for the switch projecting through said aperture and having a 45 portion overlying the aperture to substantially close the same; an inward integral indentation in the side wall of the switch housing; and spaced lugs integral with the cam engageable with opposite sides of the indentation for defining the limits of motion of the cam and for grounding the 50 cam at both of its limits of motion to the connected housing and casing so that the cam complements the apertured casing wall to assure more complete shielding between the switch and the control unit. 55

5. In an electric snap switch of the type adapted to be mounted on the back of the metal casing of another control unit: a metal switch actuating cam having a spring toggle driving connection with the movable part of the switch; a metal 60 housing for the switch; means for mechanically and electrically connecting the housing of the switch with the back of the control casing in a manner projecting part of the actuating cam through an aperture in said back of the casing 65 whereby the cam is operable from a moving part of the control and whereby the cam complements the apertured back wall of the control casing to insure the optimum electrostatic shielding between the switch and the control; and cooperating means on the switch housing and the metal cam engageable to define the limits of movement of the cam and to electrically ground the cam to the switch housing at both of its two limits of 70 movement. 75

6. In an electric snap switch of the type adapted to be mounted on the back of the metal casing of another control unit: a metal switch actuating cam having a spring toggle driving connection with the movable part of the switch; a metal housing for the switch; means for mechanically and electrically connecting the housing of the switch with the back of the control casing in a manner projecting part of the actuating cam through an aperture in said back of the casing whereby the cam is operable from a moving part of the control and whereby the cam complements the apertured back wall of the control casing to insure the optimum electrostatic shielding between the switch and the control; an inward indentation in the side wall of the switch housing adjacent to the cam; and spaced apart lugs on the cam engageable with opposite sides of the indentation for defining the limits of motion of the cam, one or the other of said cam lugs being held in engagement with said indentation by the spring force on the toggle except when the cam is

in motion to trip the switch, so that the cam is normally grounded to the switch housing.

7. In a switch assembly, the combination of a non-conducting base, a snap switch supported by the base, said switch including a non-conducting member carrying a movable contact, a metallic actuating cam and snap mechanism, a metallic shield covering the movable contact and having an opening through which a portion of the cam projects to be engageable by an actuator movable across the shield at the opposite side thereof, said cam having another portion covering a substantial part of the opening in the shield, and metal stop means connected with the shield and positioned to be engaged by and electrically connect the actuating cam at its limits of movement with the shield so that the cam is grounded and contacts with the shield in shielding the switch from any electrical instrumentality located on the opposite side of the shield. 10 15 20

NEWTON C. SCHELLENGER.
